UNITED STATES PATENT OFFICE.

JAMES KERNS, OF DEFIANCE, OHIO, ASSIGNOR TO THE BERRY MANUFACTURING COMPANY, OF UPPER SANDUSKY, OHIO.

DESIGN FOR A FOLDER FOR BALING-PRESSES.

SPECIFICATION forming part of Design No. 35,039, dated September 3, 1901.

Application filed August 1, 1901. Serial No. 70,558. Term of patent 7 years.

To all whom it may concern:

Be it known that I, JAMES KERNS, a citizen of the United States, residing at Defiance, in the county of Defiance and State of Ohio, have invented and produced a certain new and useful Design for a Folder for a Baling-Press; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to a new and original design for a folder for baling-presses; and it consists in the general shape and design of folder which is clearly illustrated in the accompanying drawings, in which—

20 Figure 1 is a perspective view of the folder, and Fig. 2 is an end elevation.

Reference now being had to the details of the design by letter, A designates a curved portion of the folder, which is on the arc of a circle and merges into a flat portion B, ²⁵ which flattened portion has lateral extensions C with parallel edges, each extension being bent at a right angle at D, the ends of the extensions being rounded.

Having thus described my invention, what I claim is—

The design for a folder for baling-presses, substantially as shown and described.

In testimony whereof I hereunto affix my signature in presence of two witnesses.

JAMES KERNS.
